UNITED STATES PATENT OFFICE.

GOTTFRIED GRILL, OF BALTIMORE, MARYLAND.

GUARD FOR VARIETY MOLDING-MACHINES.

SPECIFICATION forming part of Letters Patent No. 252,313, dated January 17, 1882.

Application filed October 10, 1881. (No model.)

To all whom it may concern:

Be it known that I, GOTTFRIED GRILL, of Baltimore city, State of Maryland, have invented certain new and useful Improvements 5 in Guards for Variety Molding-Machines; and I hereby declare the same to be fully, clearly, and exactly described as follows, reference being had to the accompanying drawings, in which—

10 Figure 1 is a side elevation, and Fig. 2 a plan view, of the device.

My invention has for its object to provide a guard of such construction as to be readily adaptable to the ordinary variety molder, and 15 designed to prevent accident to the workman.

Probably in the use of no class of wood-working machinery are accidents of more frequent occurrence than in that of the variety molder, and when they do occur they are severe and serious, resulting in the loss to the 20 workman of one or more fingers, if not of the use of the hand entirely.

I have endeavored to obviate the danger of accident by providing a guard consisting of a bell-shaped device adjustably mounted at the 25 work-side of the knives, and adapted as well to stop a flying cutter as to prevent access of the hands to the knives while in motion.

In the drawings, A is the table; a, the shaft, 30 having cutters b and pulley a', all of the ordinary construction.

In a circle about the shaft plates j j are countersunk flush with the table, leaving a dovetail annular groove between the plates, in 35 which fits a block, J, having a rod, I, which projects up through a bracket, C, and carries a clamp-lever, i, on its threaded end. The arm c of the bracket is provided at c' with brasses which are set up, by means of screws D, against 40 the top of the shaft a, steadyng both bracket and shaft.

A bell-shaped casting, d, rests around the cutters, high enough above the table to let the work pass under, and low enough to stop 45 a knife or cutter should one fly out from the shaft. Adjustability of this bell with reference to the shaft and table and its firm support are attained by means of an arm, E, threaded at f into a socket on one side of the bell,

and serrated or roughened at e', as shown. It 50 is clamped at any desired height above the table and any desired distance from the shaft by means of the bar F, the ends of which pass through the end of the arm c and carry set-screws e e.

For greater security and steadiness (though not absolutely essential) I provide two slotted arms, H h', having a bar, g, projecting downward through a lug, G, on the bell, where it is secured by a screw, k, the lower end, l, serving as a guide in bringing the wood to the cutters. The arms H h' are clamped to the bracket-arm c by screws h h, as shown.

The entire device may be readily moved around the table upon loosening the clamp i, 65 and the various adjusting devices admit of the bell being brought to any desired position.

The guard is readily applied to the ordinary molder, it being only necessary to chuck the table in a lathe and turn the groove for the 70 plates j.

Having thus described my invention, what I claim as new, and desire to secure by Letters Patent, is—

1. In combination with the table having an annular undercut groove, the bracket pivoted upon the cutter-shaft and provided with a clamp for securing it at any point in the groove, and with an adjustable bell wholly or partially inclosing the knives, as set forth. 75

2. In combination with the table having an annular undercut groove, and the bracket having adjustable bushing for the center shaft, and the clamp i J, the bell-shaped guard d, as set forth. 80

3. In combination with the guard d and bar F, secured to the guard and vertically adjustable upon the bar c, the bracket C, mounted upon the shaft, and the guide l, as set forth. 85

4. In combination with the bracket C c, adjustable about the shaft and pivoted thereon, the guard d, arms H, h', G, and E, having clamp-screws for securing and admitting of the adjustment of the parts, as set forth. 90

GOTTFRIED GRILL.
